DESIGN FOR A FRONT PIECE FOR EYEGLASSES

George S. Ratkai and David Turet,
New York, N. Y.

Application November 9, 1944, Serial No. 116,252

Term of patent 3½ years

(Cl. D57—1)

To all whom it may concern:

Be it known that we, George S. Ratkai and David Turet, both citizens of the United States and both residents of the city of New York, in the Borough of Manhattan, county and State of New York, have invented a new, original, and ornamental Design for a Front Piece for Eye-glasses, of which the following is a specification, reference being had to the accompanying drawing, forming part thereof,

In the drawing:

Figure 1 is a front view of a front piece for eyeglasses showing our new design.

Figure 2 is a bottom edge view thereof.

Figure 3 is a side edge view of the same.

We claim:

The ornamental design for a front piece for eyeglasses, substantially as shown.

GEORGE S. RATKAI.
DAVID TURET.
